DESIGN FOR A FLUORESCENT TUBE- ILLUMINATED STREET LAMP

Charles S. Davidson, Los Angeles, Calif.

Application May 23, 1941, Serial No. 101,105

Term of patent 3½ years

To all whom it may concern:

Be it known, that I, Charles S. Davidson, a citizen of the United States and residing at Los Angeles, in the county of Los Angeles and State of California, have invented a new, original, and ornamental Design for a Fluorescent Tube-Illuminated Street Lamp, of which the following is a specification, reference being had to the accompanying drawing forming part thereof, in which:

Fig. 1 is a side elevational view, broken away

in part, of a fluorescent tube-illuminated street lamp showing my new design;

Fig. 2 is a bottom plan view of the lower portion thereof the upper portion having been omitted for convenience of illustration; and

Fig. 3 is a top plan view thereof.

I claim:

The ornamental design for a fluorescent tube-illuminated street lamp, as shown.

CHARLES S. DAVIDSON.
